UNITED STATES PATENT OFFICE.

ALBERT WANNER, JR., OF NEW YORK, N. Y.

JOINT.

1,251,716.

Specification of Letters Patent.

Patented Jan. 1, 1918.

Application filed June 12, 1916. Serial No. 103,048.

To all whom it may concern:

Be it known that I, ALBERT WANNER, Jr., a citizen of the United States, residing at New York city, in the county of New York and State of New York, have invented certain new and useful Improvements in Joints, of which the following is a specification.

This invention relates to furniture and the like structures of the kind in which there are a central pedestal, staff or the like and radiating members to form basal legs for the structure or supporting arms thereon, and it consists in certain improvements whereby a knock-down structure is produced that may be readily assembled and disassembled, requiring practically no screws or other accessories to retain its parts in assembled relation, and the joint formed between said parts is exceedingly strong and durable.

My invention is herein illustrated as embodied in a clothes tree; but it will be understood that it may be applied to various structures embracing a central pedestal or staff and radiating members.

My invention consists, first, in a staff or the like having one end bifurcated in intersecting planes, and intersecting members (to form said radiating members) one or each of which is notched to receive the other, said members at their crossing portion being fitted into the bifurcations of the staff; second, in constructing the intersecting members in a structure so produced and adapting them to coöperate with the staff so that, especially with reference to the removal of material necessary to bifurcate the staff, said structure will be strong and rigid at the joint between the staff and radiating members; and, third, certain combinations and arrangements of parts hereinafter pointed out in detail and finally embodied in the claims.

In the accompanying drawings,

Figure 1 is a side elevation of a clothes tree embodying my invention;

Fig. 2 is a similar view on a larger scale, showing certain parts in section;

Fig. 3 is an isometric detail view of the staff;

Figs. 4, 5 and 6 are sectional views on the lines $x-x$, $y-y$ and $z-z$, respectively, of Fig. 1;

Figs. 7 and 9 show in side elevation and Figs. 8 and 10 show in plan the two parts of a hook-cluster forming one set of radiating members; and,

Figs. 11 and 13 show in side elevation and Figs. 12 and 14 show in plan the two parts of a leg-cluster forming the other set of radiating members.

The staff a is bifurcated (Fig. 3) longitudinally at each end, as at $b-b$ and $c-c$. It may be of round, square or any other cross-section.

In the present case there are shown four radiating portions to each hook-cluster and leg-cluster. These four portions in each instance are produced by two members arranged in intersecting planes and one or each notched (each being preferably halved) into the other.

To form the hook-cluster I provide the members $d-e$ each being sawed out, from a plate composed of laminated sheets f (Figs. 4 and 5) cemented together, to produce hooks g ; the material of the laminæ is preferably wood having the grain in adjoining sheets crossing, but it may be composed of other fibrous material, the object being to make the members $d-e$ proof against splitting, warping, etc. The member d has a vertical notch d' extending upwardly thereinto and the member e a vertical notch e' extending downwardly thereinto, and they are respectively further provided with the vertical recesses $d''-e''$ extending upwardly thereinto. The members preferably conform in contour, excepting with reference to their notches $d'-e'$; these latter being relatively reversely disposed (one down and the other up) the members may be halved into each other as shown in Figs. 1, 2, 4 and 5, the notch of each member receiving the other member, so that the structure produced appears the same in any side elevation viewed in the vertical plane of either member.

A hook-cluster thus produced is assembled with the upper end of the shaft a by forcing the intersecting or joint portion thereof down into the slots b of the staff, having first of course placed the members of the hook-cluster so that they are in planes corresponding to the vertical planes of said

slots. The width of the slots conforms to the thickness of the members of the hook-cluster, so that when the latter is in place it fits snugly and will usually require no accessories to retain it in place.

An important feature of this part of my invention is the recesses d'' e'' which are respectively of equal width with the thickness of the staff in the vertical planes of the members d e and which extend well up into said members so that well below the point h (Fig. 2) limiting the downward movement of the hook-cluster in assembling it with the staff the hook-cluster has as to each radiating portion thereof an extended bearing surface affording a substantial bearing on the side of the staff. Thus the joint between the staff and hook-cluster is greatly reinforced; if any hook g be heavily loaded, the strain 20 will come against the side of the staff rather than upon its split upper end.

To form the leg-cluster I provide the members i j . Each of these preferably consists of two legs proper i' (j') sawed out of 25 wood and joined by a web i'' (j'') formed from a plate of laminated sheets k (Fig. 6) cemented together, said sheets being composed of cross-grained wood or other suitable fibrous material; the web i'' (j'') is 30 snugly fitted into and glued or otherwise secured in opposite grooves l in the legs i' (j'). One web has an elongated notch i''' extending vertically into it from its lower edge and the other has a similar notch j''' 35 extending into it from its upper end. Each web is of course thinner than the legs proper i' j' , so that the inner edges m of the latter, which are well extended vertically, form shoulders. The members i j thus produced, 40 conforming in contour with each other substantially exactly excepting for disposition of their notches i''' j''' , are halved into each other as shown in Figs. 1, 2 and 6, the notch of each member receiving the other member substantially as in the case of the members of the hook-cluster.

A leg-cluster thus produced is assembled with the staff a by placing the latter over the intersection of the leg-cluster so that its 50 bifurcations c register with the webs of the leg-cluster and then forcing the staff downwardly. The width of the notches i''' j''' conforms with the thickness of the webs, so that when the staff is in place the parts fit 55 snugly and will usually require no accessories to keep them together.

An important feature of this part of my invention is the bearing surfaces or shoulders m which in the case of each member of the leg-cluster are spaced apart a distance equal to the thickness of the staff in the plane of said member, so that the bifurcated part of the staff is abutted on opposite sides by the shoulders m , extending the full vertical length of the joint. Thus, the four

prongs or projections at the lower part of the staff formed by bifurcating the staff at c are kept from spreading apart, so that in effect the lower end of the staff, when assembled with the leg-cluster, is as substantial and rigid as if not bifurcated. As to this part of my invention I do not wish to be limited to the structure of the webs as herein described and shown or to their being parts formed separately from and attached to the legs proper, the broad idea claimed being leg forming members each thinner in its intersecting portion, thus forming the shoulders m or equivalent.

Having thus fully described my invention, so what I claim as new and desire to secure by Letters Patent is:—

1. A structure of the class described including a staff bifurcated at one end in intersecting longitudinal planes, and radiating members consisting of a plurality of intersecting members one of which is notched into the other to form a joint, the joint forming portions of the intersecting members being received respectively in the bifurcations of the staff and each intersecting member having a recess receiving and fitting snugly the unbifurcated part of the staff immediately inward of its bifurcated end.

2. A structure of the class described including a staff bifurcated at one end in intersecting longitudinal planes, and radiating members consisting of a plurality of intersecting members one of which is notched into the other to form a joint, the joint forming portions of the intersecting members being received respectively in the bifurcations of the staff and each intersecting member having opposite inwardly facing fixed bearing surfaces bearing against opposite sides of the staff.

3. A structure of the class described including a staff bifurcated at one end in intersecting longitudinal planes, and radiating members consisting of a plurality of intersecting members one of which is notched into the other to form a joint, the joint forming portions of the intersecting members being received respectively in the bifurcations of the staff and each intersecting member having opposite inwardly facing fixed bearing surfaces bearing against opposite sides of the bifurcated part of the staff.

4. A structure of the class described including a staff bifurcated at one end in intersecting longitudinal planes, and radiating members consisting of a plurality of intersecting members one of which is notched into the other to form a joint, the joint forming portions of the intersecting members being received respectively in the bifurcations of the staff and each joint-forming portion being thinner than and immovably connected with the portions of the corresponding member immediately outward

thereof and thus forming fixed shoulders bearing against opposite sides of the bifurcated part of the staff.

5. A structure of the class described including a staff bifurcated at one end in intersecting longitudinal planes, and radiating members consisting of a plurality of intersecting members, each member including a pair of outer portions having opposed 10 grooves and a connecting web fitted into

said grooves, one of said webs being notched into the other to form a joint and such joint having the webs respectively received in the bifurcations of the staff and each web being thinner than said outer portions, whereby 15 to form inwardly facing bearing surfaces bearing against opposite sides of the bifurcated part of the staff.

In testimony whereof I affix my signature.

ALBERT WANNER, JR.
